UNITED STATES PATENT OFFICE.

FELIX MARCUS, OF PHILADELPHIA, PENNSYLVANIA, ASSIGNOR TO WILLIAMS & MARCUS COMPANY, A CORPORATION OF PENNSYLVANIA.

TICKET FOLDING AND CUTTING MACHINE.

952,456.

Specification of Letters Patent. Patented Mar. 22, 1910.

Application filed March 22, 1909. Serial No. 435,123.

To all whom it may concern:

Be it known that I, FELIX MARCUS, a citizen of the United States, residing at Philadelphia, in the county of Philadelphia and State of Pennsylvania, have invented certain new and useful Improvements in Ticket Folding and Cutting Machines, of which the following is a specification.

This invention consists of a comparatively simple but extremely efficient machine designed particularly for cutting and folding tickets preparatory to putting the same in book form.

The invention resides particularly in the peculiar feeding, cutting, and folding devices by which a sheet of paper of suitable size, printed or unprinted as desired, may be fed into the machine and cut into a number of strips, each strip being folded and fed to a box or hopper located at a predetermined part of the machine.

For a full understanding of the invention, reference is to be had to the following detail description and to the accompanying drawings, in which—

Figure 1 is a vertical longitudinal section of a machine embodying the invention; Fig. 2 is a top plan view; Fig. 3 is a fragmentary plan view showing more clearly the arrangement of the adjusting device co-operating with the folding rolls; Fig. 4 is a sectional view of the same; Fig. 5 is a side elevation of the gear box; Fig. 6 is a section of the same, and Fig. 7 is a perspective view of a ticket cut and folded as when operated upon by the present machine.

Throughout the following detail description, and on the several figures of the drawings, similar parts are referred to by like reference characters.

In carrying out the invention it is contemplated that the various parts of the machine be mounted upon a suitable frame 1, an end portion of which extends upwardly as shown at 2. At one end of the frame 1 is located a feeding table 3 above which are arranged on shafts 4 and 5 the tension rolls 6 and 7 respectively. The shafts 4 and 5 are connected together by yoke plates 8, said plates being connected by a transverse yoke 9. The rolls 6 are in contact with rolls 6^a, the peripheral portions of which extend through openings in the table 3. A series of feed rollers 10 are adapted to feed the paper from the rolls 7 to the cutters 11 which are

mounted upon cutter shafts 12. The sheet of paper is cut into a number of strips as it passes between the cutters 11 and these several strips are fed to folding rolls 13 and 14 arranged in the same horizontal plane, small rubber feeding disks 15 being arranged above the rolls 13 and carried by vertical standards 16 mounted in suitable brackets 17 secured to the frame work of the machine. A plurality of adjusting plates 18 are mounted on a transverse portion of the frame of the machine and adjacent to the folding roll 14, said adjusting plates having a plurality of upwardly curving guide fingers 19 extending therefrom toward the feeding disks 15 and also having longer and downwardly curved fingers 20 extending partially into the space between the upper portions of the feed rolls 13 and 14. Certain of the strips of paper cut by means of the rotary cutters 11 are stopped in their forward movement by means of the adjusting plates 18, the foremost edges of said strips passing between the fingers 19 and 20. Just as the strips aforesaid are stopped by the plates 18, and while arranged above the folding rolls 13 and 14, a plurality of folding devices consisting of fingers 21 supported by arms 22 on a rock shaft 23 move downwardly and by engaging with the upper sides of said strips, the latter being shown at 24, these strips are partly folded and caused to pass downwardly between the contacting folding rolls 13 and 14 from whence they are dropped into a hopper or box 25. Those strips which drop into the boxes 25 are retained by means of pressure fingers 26 carried by arms 27 projecting from another rock shaft 28. As a ticket or strip of paper when folded drops into the box 25, the fingers 26 are upraised by reason of actuation of the arms 27, but as soon as the ticket is in the box, the arms 27 are so timed in operation as to move downwardly and cause the fingers 26 to engage and retain the ticket just dropped by slight pressure in the manner shown in Fig. 1.

It is contemplated that a certain number of the strips, four in the present instance, into which the sheet is cut by the cutters 11, shall be folded and drop into boxes 25. Other strips or tickets after being cut are fed over the rolls 13 and 14 upwardly on a runway 29 by means of suitable feed rolls 10^a and feeding disks 15^a. Those tickets which

are not folded by the folding rolls 13 and 14 but pass outwardly between the rolls 10^a and 15^a are finally folded by coacting folding rolls 13^a and 14^a located on the elevated portion 2 of the frame 1. Coöperating with the rolls 13^a and 14^a are the folding fingers 21^a similar to the fingers 21 and which are carried by arms 22^a operated in any suitable manner from a moving part of the machine.

10 Adjusting plates 18^a of course coöperate with the rolls 13^a and 14^a.

It will be observed that on a shaft 30 is mounted a cam 31 said cam coöperating with a roller contact on the extremity of a rocker arm 32. The arm 32 is connected with the shaft 23 and rotation of the cam 31 moves the arm 32 up and down imparting corresponding movement of course to the folding fingers 21 carried by the shaft 23. On the 20 shaft 30 is also mounted a gear 33 for eccentric connection at 34 with a rod 35 connected with an arm 36 on the shaft 28. The arms 27 carrying the pressure fingers 26 are operated by back and forth movement of the 25 arm 36 which actuates the shaft 28, and said arm 36 is also connected by a rod 35^a with a similar arm 36^a on the shaft 28^a on the elevated portion 2 of the frame, said shaft 28^a having arms 27^a supplied with pressure 30 fingers 26^a. The fingers 26^a perform the same function with respect to tickets dropped into the hopper 25^a as described with reference to the parts 25 and 26.

It will be observed that the outermost tension rolls 6 to which the paper is fed preparatory to being cut into strips or tickets is adapted for slight upward movement. The purpose of this is to enable the paper as it is fed to the machine to be placed with 35 its lower inner edge in contact with stop fingers 37 adapted to be projected above the plane of the table 3 through openings therein. When the rolls are slightly elevated 40 above the table 3 the fingers 37 project above the table to facilitate accurate placement of the sheet fed to the machine. As soon as the sheet is in position, however, the rolls 6 are dropped into contact with the rolls 6^a and the fingers 37 simultaneously lower so as not 45 to project above the table and in order to permit the rolls 6 and 7 to pass the sheet 50 onward to the feeding rolls 10. The means for elevating the rolls 6 as above described and operating the fingers 37 comprises the 55 devices now to be described. It may be observed at this time that the various shafts carrying the rolls above mentioned are intergeared in any suitable way and timed for operation in a proper manner of the parts

supported thereby. The fingers 37 project 60 upwardly from arms 38 extending laterally from a shaft 39. Also from the shaft 39 is a long arm 40 having a roller at its outer end adapted to be engaged by a cam 41 on the shaft 42. The intermittent up and down 65 movement of the arm 40 imparts corresponding movement to the fingers 37 in an obvious manner projecting or withdrawing said fingers from coaction with the sheet of paper on the feeding table 3. Spaced bearings 43 70 are guided by pins 44 or like members, are connected at their upper ends to the yoke plates 8. The members 43 are moved up and down by a cam on the shaft 42 and in this manner the upper tension roll 6 is slightly elevated 75 at intervals of time to permit the sheet to be fed below said roll preparatory to be fed onward in the machine. The gear 45 is rigid with the shaft 42 and is provided with a series of recesses therein. A plurality of 80 spring pressed pins 49 are carried by the member 46 and are adapted to be projected at predetermined intervals into the gear 45 by the stationary cam member 50 interlocking the gears. 85

Having thus described the invention, what is claimed as new is:

In a machine of the class described, the combination with a frame, of a feed table, tension rolls arranged above said feed table, 90 cutters mounted adjacent said rolls, folding rolls mounted adjacent said cutters, means for slightly elevating the tension rolls at predetermined intervals, a plurality of feeding rolls adapted to receive a sheet from the tension rolls and pass the same through the cutters where it is cut into strips as it passes from said rolls, a part of said strips passing through the folding rolls, the remainder passing forward to the folding rolls located 100 farther on the machine frame, adjusting plates adjacent to the folding rolls to stop the strips of paper above the folding rolls, folding fingers, arms supporting the folding fingers, a rock shaft carrying said arms, 105 means for moving the arms up and down to impart similar movement to the folding fingers, a hopper beneath the folding rolls, and pressure fingers movable into and out of the hopper for retaining the folded strip dropped 110 thereinto.

In testimony whereof I affix my signature in presence of two witnesses.

FELIX MARCUS.
